FENDER SKIRT

Dock Price, Jr., 4347 4th St. SE., Apt. 3,
Washington, D.C.

Filed Sept. 13, 1965, Ser. No. 86,971

Term of patent 3½ years

(Cl. D14—6)

FIGURE 1 is a side elevational view of a fender skirt embodying my new design;

FIGURE 2 is a sectional view thereof taken substantially along line 2—2 of FIGURE 1; and

FIGURE 3 is a reduced scale perspective view thereof showing the same mounted on the rear fender of an automotive vehicle.

The characteristic feature of my design resides in the centrally disposed open mesh area substantially parallel with the edge of the skirt.

The fragmentary portions of a vehicle shown in broken lines in FIGURE 3, are included for illustrative purposes only.

I claim:

The ornamental design for a fender skirt, as shown and described.
